(57) **CLAIM**

The ornamental design for a spout, as shown and described.

DESCRIPTION

FIG. 1 is a perspective view taken from the top, front, and right side of a spout showing my new design;

FIG. 2 is a top plan view of the spout shown in FIG. 1;

FIG. 3 is a bottom view of the spout shown in FIG. 1;

FIG. 4 is a front elevational view of the spout shown in FIG. 1;

FIG. 5 is a rear elevational view of the spout shown in FIG. 1;

FIG. 6 is a left elevational side view of the spout shown in FIG. 1;

FIG. 7 is a right elevational side view of the spout shown in FIG. 1;

FIG. 8 is a perspective view taken from the top, front, and right side of another embodiment of a spout showing my new design;

FIG. 9 is a top plan view of the spout shown in FIG. 8;

FIG. 10 is a bottom view of the spout shown in FIG. 8;

FIG. 11 is a front elevational view of the spout shown in FIG. 8;

FIG. 12 is a rear elevational view of the spout shown in FIG. 8;

FIG. 13 is a left elevational side view of the spout shown in FIG. 8; and,

FIG. 14 is a right elevational side view of the spout shown in FIG. 8.

The broken lines are for illustration purposes only and form no part of the claimed design.
